UNITED STATES PATENT OFFICE.

PHILIP H. DEIS, OF WASHINGTON, DISTRICT OF COLUMBIA.

FOLDING RACK FOR POULTRY, &c.

No. 858,159.

Specification of Letters Patent.

Patented June 25, 1907.

Application filed February 27, 1907. Serial No. 359,664.

To all whom it may concern:

Be it known that I, PHILIP H. DEIS, a citizen of the United States, residing in Washington, District of Columbia, have invented 5 certain new and useful Improvements in Folding Racks for Poultry, &c.; and I do hereby declare the following to be a full, clear, and exact description of the invention, such as will enable others skilled in the art to which 10 it appertains to make and use the same, reference being had to the accompanying drawings, and to letters of reference marked thereon, which form a part of this specification.

In devising the rack herein set forth, I 15 have had particu'larly in view, among other objects, to provide a means for displaying poultry, meats, etc., and for holding articles of various kinds, which shall not only make an attractive store fixture but shall be capable 20 of readily folding into convenient and compact form for moving about or storing away, if necessary, be readily capable of being kept in a clean and sanitary condition, be strong and durable and relatively inexpensive 25 in construction, and adjustable as to certain of its parts so as to accommodate different numbers of articles supported while displaying them to the best advantage.

My invention will be found fully illustrated 30 in the accompanying drawings, wherein,

Figure 1 is a side view of the rack; Fig. 2 a horizontal sectional view in the plane of one of certain sleeves when the folding arms connected with said sleeve are extended; Fig. 3 is a detail showing the bag or paper holding skewer; Figs. 4, 5 and 6 show various forms of suspending devices carried by said arms; and, Fig. 7 illustrates how the arms and their 35 accessories may be counterbalanced where the construction renders the same desirable or necessary.

In these drawings, *a* designates a tubular upright and *b* a suitable stand or bracket in 45 which said upright may be revolvably mounted, it being contemplated to make the rack capable of turning so that the articles may be conveniently placed thereon and removed therefrom; the lower end of the upright projects 50 down into the stand and may directly rest on an anti-friction device *c* carried by the stand, the upright having a flange *d* which seats on said anti-friction device. The upright is preferably surmounted by a receptacle 55 *e* for a ball of twine *f*, which receptacle may form a convenient medium, as shown,

for displaying advertisements. On the upright are arranged sleeves *g* which fit snugly but slide freely thereon, and each of said sleeves is surrounded by a collar *h* provided 60 with pairs of radial spaced ears *i*, the collars being brazed or shrunk onto the sleeves or otherwise permanently secured thereto so as to be practically integral therewith.

j designates arms having an inverted T- 65 shaped cross-section for substantially their whole length, the inner end-portions thereof, however, being left flat or plain. Each arm is pivotally connected with one of the sleeves by having its inner or plain end inserted between two of the ears *i* and a pin *k* passed through it and the ears.

l denotes other sleeves brazed or shrunk onto the upright (being thus non-slidable) and *m* other collars brazed or shrunk onto 75 said sleeves and having pairs of radial spaced ears *n*. Each arm *j* has formed on its top side a pair of spaced ears *o*. The arms are connected with the upright in such manner that when the sleeves *g* are moved up or 80 down the arms unfold or fold, respectively, through the medium of links or braces *p* which have their ends inserted between the ears *n* and *o* of the sleeves *l* and the arms, respectively, and pivotally held therein by pins 85 *q*. It will be understood that according to the strength of the arms and the weight which they may have to sustain, the ears *o* may be disposed or formed at different distances from the free ends of the arms so that 90 the latter may derive support through the braces to the best advantage.

On the arms are arranged suspending devices such as, for instance, of the types shown in Figs. 4, 5 and 6; in each of these devices 95 there is a body part *r* having an inverted T-shaped slot *s* in the top thereof, whereby said devices may be slid onto the arms and sustained thereby, and carrying a downwardly projecting thumb-screw *s'* whereby, 100 when the suspending devices have been placed on the arms and disposed in any desired arrangement, they may be securely held where adjusted. By making the inner ends of the arms plain or flat, as above described, 105 the suspending devices may be placed on the arms or removed therefrom at both ends of its T-shaped portion.

In Fig. 4 the suspending device is shown as having a double sharpened hook *t* for meats 110 and the like; in Fig. 5, as having a double forked hook *u* for sustaining poultry or the

like, the legs of the fowls being intended to be received between the prongs of the hook; and in Fig. 6, as having plain hooks *v* for holding hats, coats and other similar articles.

- 5 When the arms are extended they stand, say, horizontally and they are held in this position by the following means: A tubular holder *w* is screwed into each sleeve *g*, and in this holder is arranged a locking-pin *x* having a knob or button *y* at its outer end and its inner end adapted to enter a hole *z* (of which there are two, one for each sleeve *g*) when the arms are properly extended; a spiral spring 1 is coiled about the pin and bears at 10 its ends against shoulders 2 and 3 on the inside of the holder and on the pin. When the arms are properly extended the pin snaps into the hole *z* and locks the parts in that position; when the arms are to be folded, the 15 pin is drawn out sufficiently to clear the hole.

- In Fig. 1 is shown a means for holding paper bags or wrapping paper and for guiding the cord *f*. Here 4 is a cylindrical socket permanently secured to one of the arms at the 20 free end thereof and 5 a skewer having a knife-shaped cross-section; (Fig. 3) and arranged in and projecting from said socket; the skewer slides in the socket and is normally retracted by a spiral spring 6 coiled 25 about it within the socket and interposed between shoulders 7 and 8 formed on the skewer and the inside of the socket, respectively. By means of a thumb-screw 9 the skewer may be held more or less projected 30 temporally. A button 10 provided with a guiding eyelet 11 for the cord *f* may be removably secured on the sharpened free end of the skewer by means of a thumb-screw 12. This button both sheathes the sharpened end 35 of the skewer and, when paper bags or sheets of wrapping paper have been placed thereon and the skewer released by easing the thumb-screw 9 so that the spring will retract it, acts as a follower to clamp the bags or sheets between itself and the end of the socket 4 and 40 maintain the bags or sheets in a neat and compact form. Since the skewer has a knife-like cross-section, its cutting edge bearing up, the bags or sheets may be readily re-

moved therefrom by drawing downwardly 50 on them without tearing them and scattering fragments of paper about.

It will be observed that the braces *p*, by extending upwardly from the arms *j* and also by being connected therewith substantially 55 midway the length thereof suspend said arms during the opening and closing operations; this makes it easier to open and close the arms than it would be if the braces extended downwardly from the arms, and besides leaves 60 a clear space beneath for the articles hung from the arm.

In the larger sizes of the rack where the weight of the arms and their accessories may make it desirable the same may be counter- 65 balanced by a weight 13 movable vertically in the upright and connected with a pin 14 carried by the sleeve *g* by a cord or other flexible device 15 which runs over a pulley 16 journaled inside of the upright; the pin ex- 70 tends through the upright and its up and down movement may be permitted by a slot 17 in the upright.

Having thus fully described my invention, what I claim and desire to secure by Letters 75 Patent is:

In a folding rack, the combination of a tubular upright, radial sustaining arms, braces pivotally connected with said arms, means for pivotally connecting said braces with the 80 upright, a sleeve arranged on said upright and movable longitudinally thereof, said arms being pivotally connected with the sleeve and said upright being vertically slotted, a pin carried by said sleeve and ex- 85 tending through the slot of said upright, a pulley journaled in said upright, a weight arranged to move in said upright, and a flexible connection between said pin and the weight, said connection being extended over the 90 pulley.

In testimony, that I claim the foregoing, I have hereunto set my hand this 26th day of February, 1907.

PHILIP H. DEIS.
